COIN-CONTROLLED MECHANISM

Harry L. Neer, Beech Grove, and Clifford H. Was-
son, Indianapolis, Ind., and Raymond L. Neer,
Jacksonville, Fla., assignors to Nik-O-Lok
Company, Indianapolis, Ind., a corporation of
Indiana

Application August 6, 1941, Serial No. 405,584

25 Claims. (Cl. 194—65)

The present invention relates to a coin controlled mechanism; and, while the disclosed mechanism, or parts thereof, may be utilized in other connections, the invention will be particularly described in connection with coin controlled locks for doors, or the like.

The prior practical art

The field to which the present invention pertains is by no means new. For many years, coin controlled locks have been in use in public toilets, lavatories, bath houses, and the like; and those locks have been, broadly, quite successful. However, the locks which have been in use heretofore have been subject to defects of various types; and it is the primary object of the present invention to provide, in mechanisms of the character here under discussion, refinements such as to overcome all of such defects.

Among the defects which have existed in previously known locks of the character here under consideration are the fact that, by inserting slugs of various types, or by inserting a match in just the right way, or by inserting folded pieces of paper, the lock can be released to permit operation of the latch; that the latch of prior structures can be operated, from inside the enclosure, by rotation of the operating handle in one direction only; that forcible operation of the outer handle of the mechanism can sometimes operate the counting register, and can sometimes cause the parts of the lock to be caught in a position such as to prevent the insertion of a coin thereinto; the fact that it is difficult to remove material wadded into the coin receiving slot; and the fact that the latch can be operated by the insertion of a blade between the door and its frame, or by the insertion of a piece of cloth between the door and its frame. These faults of previously known coin controlled locks, as well as other defects which will appear as the description proceeds, are overcome by the refinements which we have disclosed in the present application.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a front elevation of an assembly plate upon which the parts of the lock of the present

invention are assembled, with most of the lock mechanism removed therefrom;

Fig. 2 is a similar view after the assembly of further elements of the organization; and

Fig. 3 is a similar view of the complete lock mechanism;

Fig. 4 is a top plan view of the lock mechanism;

Fig. 5 is a bottom plan view thereof;

Fig. 6 is a side elevation seen from the left-hand side of Fig. 3;

Fig. 7 is a side elevation seen from the right-hand side of Fig. 3, the lock being shown mounted upon a fragment of a door;

Fig. 8 is a front elevation of a housing for the lock mechanism;

Fig. 9 is a side elevation thereof viewed from the left-hand side of Fig. 8;

Fig. 10 is a front elevation of a keeper for association with the lock;

Fig. 11 is a side elevation thereof, viewed from the right-hand side of Fig. 10;

Fig. 12 is a view similar to Fig. 3 but showing a modified form of lock mechanism; and

Fig. 13 is a view similar to Fig. 8, and showing a housing for association with the mechanism of Fig. 12.

The latch-bar mounting

Referring more particularly to the drawings, in Fig. 1 we have shown the assembly plate 20 upon which the lock mechanism is to be built up. In Fig. 1, there are shown yokes 21 and 22 suitably secured to the assembly plate near the top thereof, the yoke 21 being formed with a U-shaped portion 23 and the yoke 22 being formed to provide a deeper U-shaped portion 24 in which is journaled a roller 25. The latch bar 26 is slidably mounted upon the assembly plate 20, being guided in its movement by the aligned U-shaped portions 23 and 24 of the yokes 21 and 22. The forward surface of the latch bar 26, adjacent its beveled, projecting end, bears against the roller 25; and, at its opposite end, the rearward face of the latch bar is formed with a notch 27 in which is journaled a roller 28 which bears against the front surface of the assembly plate 20. Because of this arrangement, wear upon the latch bar 26 and the associated elements resulting from movement of the latch bar enforced by the engagement of the bevelled end thereof with the keeper, is minimized.

To the upper edge of the latch bar 26 is secured a plate 29 carrying, adjacent its right-hand end, an ear 30 which projects upwardly above

the latch bar. As is clearly shown in Figs. 4 and 7, this ear is carried on a portion of the plate 29 which projects forwardly beyond the yoke 23, so that the yoke 23 does not interfere with movement of the ear toward the right from the position illustrated in Fig. 1. The ear 30 is provided, as will appear from the description to follow, for cooperation with a pin operable by a pass key to permit withdrawal of the latch bar without inserting a coin into the lock, and without affecting the counting register.

The latch bar 26 is normally held in projected position by a spring 31 connected at one end to a plate 32 suitably secured to the assembly plate, and at its opposite end to a cotter pin 33 secured in the latch bar 26. As is clearly shown in Fig. 4, the rearward surface of the latch bar is cut away as at 34 to provide a space between the latch bar and the assembly plate 20 intermediate the ends of the latch bar.

Latch-bar operation from within the enclosure

Received in said space and adapted to engage the right-hand end of the space 34, as viewed in Fig. 1, is the end of a back tumbler lever 35 pivotally secured to the assembly plate 20 by a screw 36. Said lever 35 is formed with a cam surface 37 positioned closely adjacent an operating pin 38 carried by the back shaft 39 which is projected through a suitable opening in the assembly plate 20. Said shaft 39, when the lock is assembled upon a door, projects, as is clearly shown in Fig. 7, through the door to carry an operating handle 40 on the inside of the door; and it will be obvious that oscillation of the shaft 39 in a clockwise direction as viewed in Fig. 1 will cause clockwise movement of the lever 35 about its pivotal axis 36 to shift the latch bar 26 to the right, against the tendency of the spring 31, to withdraw the latch from engagement with its keeper, thereby permitting the door to be opened.

In practice, it has been found that people occasionally become excited when, in trying to open the door of a toilet from the inside, they find that the handle will not move in one direction; and, perhaps because of a touch of claustrophobia, scream and shout for help without even trying to turn the handle in the opposite direction.

For that reason, we have provided means, in the present mechanism, whereby the handle 40 may be turned in either direction to withdraw the latch. Upon a stationary post 41 carried by the assembly plate 20, there is journaled a supplemental tumbler lever 42, one arm 44 of which lies in contact with a surface 45 of the lever 35, and the opposite arm of which provides a surface 43 lying closely adjacent the pin 38. It will be clear that counterclockwise movement of the shaft 39 will swing the lever 42 in a clockwise direction about its post 41, whereby the arm 44 of said lever, in cooperation with the surface 45 of the lever 35, will swing the lever 35 in a clockwise direction about its pivot 36 to shift the latch bar 26 to the right.

It has been found in practice that users of these locks sometimes, either maliciously or ignorantly, exert great force upon the handles thereof. It will be obvious that, if the pin 38 should be forced, in any way, to move past the end of the surface 43 on the lower arm of the lever 42, it would then become impossible, by any kind of operation of the handle 40, to withdraw the latch bar 26. Therefore, we prefer

5 to provide a stop member 38' so positioned with relation to the pin 38 as to stop that pin positively against rotation to a point at which the pin 38 would be disengaged from the surface 43 of the lever 42.

The coin-actuated pawl

10 A screw 46 is formed with an intermediate shaft portion upon which is journal mounted 15 a coin pawl 47, said pawl being spaced from the assembly plate 20 by a collar 48 (see Fig. 7). The nose 49 of said pawl is notched as at 51 20 to form two sharp edges 50 and 52, most clearly illustrated in Figs. 1 and 2, for a purpose which will appear hereinafter. A cotter pin 53 passes through the lever 47 to support one end of a spring 54, the function of which is normally 25 to hold the pawl 47 in the position illustrated in Figs. 1, 2, and 3. The rear side of the pawl 47 carries a stop screw 55 which, in the illustrated position of said pawl, engages against a number 56 carried by the plate 20 to limit movement of the pawl under the influence of the spring 54.

25 *The front tumbler trip*

30 A screw 57 secured to the assembly plate 20 provides a pivotal mounting for a front tumbler trip 58, one arm 59 of which is received within the space 34 in a position to be engaged by the 35 left-hand end wall 60 of said space, upon movement of the latch bar to the right, resulting from tripping of the latch bar by the keeper as the door is closed. At its opposite end, the tumbler 58 carries a finger 61 projecting forwardly from the main body of the tumbler for a purpose later to be described. A perforated ear 62 is secured to the lower arm of the tumbler trip 58 as an anchorage for a spring not shown in Fig. 1, but shown in, and described in connection with, 40 Fig. 2 hereinafter.

The coin-carriage track arms

45 A post 63, stationarily mounted on the assembly plate 20, is bifurcated adjacent its forward end, and a pin 64 traverses the bifurcated portion of said post to form a journal mounting for a forward coin carriage arm 65. A second post 66 is likewise bifurcated at its outer end to guide the oscillating movement of said coin carriage 50 arm 65; and a spring 67 is secured at its opposite ends to cotter pins respectively carried by said arm 65 and said post 63 to urge the free end of the arm 65 rearwardly toward the assembly plate 20 and into contact with the base of the kerf between the furcations of the post 66. A stationary arm 68 spaced from the arm 65 by a distance somewhat less than the diameter of the coin intended to operate the lock, but greater than the diameter of any coin of less 55 value, is stationarily carried by the post 66 just in front of the lever 35. As will appear from the following description, the arms 65 and 68 cooperate to support a coin during the movement of the parts necessary to release the lock 60 for authorized operation.

65 Projecting forwardly from the front face of the latch bar 26 is a flange 69, most clearly illustrated in Figs. 1, 2, and 4, for a purpose which will appear hereinafter.

70 *The latch-bar blocking means*

The plate 20 carries an ear 70 in a plane between the front surface of the assembly plate and the front surface of a top catch block 71 secured 75 to the assembly plate, said block being suitably

cut away, in the manner most clearly shown in Figs. 6 and 7, for the accommodation of said ear 70. Threadedly mounted in the block 71 is a screw 72, most clearly shown in Figs. 1, 4, and 6. In the projected position of the latch bar 26, the ear 70 is located to the right of the inner end 73 (see Fig. 4) of the screw 72. In the retracted position of the latch bar, the ear 70 is positioned to the left of said inner end 73 of the screw. The part-spherical head 74 of the screw 72 is formed with a polygonal socket 75 for the reception of a suitably shaped wrench; and said screw may be rotated, by operation of such wrench, to project its end 73 into the path of the ear 70. If the screw is so projected while the latch bar 26 is in the position of Fig. 4, withdrawal of the latch by operation of either the inner handle or the outer handle is rendered impossible. If, however, the latch bar is held in retracted position while the screw 72 is projected into the path of the ear 70, the latch bar will thereby be retained in withdrawn position, so that the door will be freely operable.

Frequently, when a ballroom or banquet hall is rented for a private party, it is desirable to render pay toilet booths operable without the deposit of the usual coin; and the mechanism just above described is provided for that purpose. We have also provided mechanism whereby, when the latch is so retained in withdrawn position, the deposit of a coin by a person desiring to use the toilet and who has failed to note that the door is freely operable, is automatically prevented. One arm 76 of a lever 77, pivotally mounted upon the block 71 by a screw 78, is positioned in the path of the part-spherical head 74 of the screw 72. As the screw is moved inwardly, the head 74 operates upon the lever arm 76 to swing said lever in a counterclockwise direction, thereby moving the depending arm 79 to the right, as viewed in Fig. 1, to close the coin slot in a manner which will become apparent as the description proceeds.

Preferably, the screw 72 is formed with a flat side with which cooperates a ball 80 received in a bore in the block 71 intersecting the threaded seat of the screw 72, and urged toward said screw by a spring 81 backed up by a screw 82.

Near the base of the assembly plate 20, a bracket 83 is secured to said plate by bolts 84, said bracket supporting a counting register 85 including a ratchet shaft 86. Movement of said shaft in one direction through a predetermined angle will cause operation of said register, while movement of said shaft in the opposite direction will not affect the register.

The front tumbler assembly

The front tumbler 87 comprises a barrel journaled upon the projecting end of the shaft 39, and carrying, at its forward end, a plug 88, held against rotation with respect to the tumbler, and formed with a kerf 89. Said tumbler comprises also a plate portion 90 substantially parallel with the assembly plate 20. Near its base, the tumbler 87 is formed with a tangentially projecting finger 91 which, as is clearly shown in Fig. 2, is positioned for cooperation with the finger 61 of the front tumbler trip 58. Near its outer end, the tumbler 87 is provided with a projecting finger 92 for a purpose later to be described.

A plate 93 is formed with an aperture 94 whereby said plate is journal mounted upon the projecting head of the plug 88. The lower projecting end 95 of the plate 93 receives a pin 96 through

5 which is pivotally connected to said plate end one end of a pitman 97 formed, adjacent its opposite end, with a slot 98 guided upon the shaft 86 of the register 85. Adjacent said guided end, the pitman 97 is formed with an angularly projecting slot 99 for a purpose later to be described.

10 Rearwardly projecting from the plate 93 is a stop post 100 positioned in the path of the finger 92 of the tumbler 87, whereby the plate 93 will be caused to partake of clockwise movement of the tumbler 87 only after said tumbler has been turned through a predetermined angle.

15 The tumbler 87 further comprises a tangentially projecting arm portion 101 substantially perpendicular to the portion 90. Adjacent its outer end, the arm 101 is formed with an aperture 102 for a purpose later to be described. Intermediate its ends, the arm 101 is formed, on its right-hand surface, with a socket 103 defining a downwardly 20 and forwardly facing shoulder 104. It will be seen that, upon clockwise movement of the tumbler 87, the base of the socket 103 will come into contact with the nose 49 of the pawl 47, and that an attempt to continue such movement of the 25 arm 101 will cause the edge 50 of said pawl to slide up into contact with the shoulder 104. A headed brass pin 105 is positioned immediately beyond the shoulder 104 so that, if in any way the pawl should escape the shoulder 104, the pawl edge 50 will engage said pin head 105. Either of these engagements will, of course, prevent further clockwise movement of the arm 101; and either of those engagements will, of course, take place before the end of the arm 101 comes into 30 operative contact with the flange 69 on the latch bar 26.

35 The various sharp edges and shoulders on the pawl and on the arm 101 are provided for the purpose of penetrating or chewing up any relatively soft material, such as wood, cardboard, or the like, which may be inserted into the lock in an effort to actuate the same without depositing the required coin.

40 From an inspection of Fig. 2, it will be seen that the arm 79 of the lever 77 cooperates with the arm 101 of the tumbler 87; so that the counterclockwise movement of the lever 77 resulting from projection of the screw 72 above described, will swing the arm 101 in a clockwise direction.

45 A U-shaped strap 106 is secured to the assembly plate 20 by any suitable means such as the bolts 107, said strap including end walls 108 and 109 projecting perpendicularly forward from the plane of the assembly plate 20. A spring 110 is anchored at one end upon a cotter pin 111 secured to the tumbler 87 adjacent the root of the arm 101, and is anchored at its opposite end upon a cotter pin 112 secured to the wall 109, said spring resiliently holding the tumbler in the position illustrated in Fig. 2, the degree of movement of said tumbler in response to the tendency 50 of the spring 110 being limited by the pin 41.

The front tumbler trip springing arrangement

55 A light spring 113 is anchored at one end upon the cotter pin 111 and at its opposite end upon the ear 62 secured to the tumbler trip 58. It is particularly to be noted that the spring 113 is thus located at an acute angle greater than 45 degrees relative to the path of movement of the ear 62. The spring 113 is very light and, in the illustrated position of the parts, is substantially completely relaxed. Thus, although the portion 60 of the latch bar contacts the end 59 of the tumbler trip 58 upon withdrawal of the latch bar by operation of the inner handle 40, and

causes some movement of the tumbler trip 58, the particular arrangement of the spring 113 is such that said spring adds substantially nothing to the resistance offered by the spring 31 to such movement of the latch bar. The function of the spring 113 is to shift the tumbler trip in a counterclockwise direction upon a predetermined angular movement of the tumbler 87 in a clockwise direction; and it will be noted that, because of the particular arrangement of the spring 113, that spring is placed under tension by the initial movement of the tumbler 87 in a clockwise direction, so that it is ready to apply force to the tumbler 58 as soon as the finger 91 moves out of the path of the finger 61.

The slug ejector mechanism

A spacer post 114 (see Fig. 4) is formed at its outer end to provide a journal mounting for one end 115 of an ejector body 116. Said post 114 is bored to pass a screw 117 which threadedly engages the assembly plate 20 to mount said post 114 and the ejector body 116 on said assembly plate 20. The ejector body 116, as is clearly shown in Figs. 4 and 7, comprises parallel spaced parts joined by aligned rings 118 and 119 in which is reciprocably mounted an ejector pin 120. A pin 121 traverses said ejector pin 120 at a point intermediate its ends and forms an abutment for one end of a spring 122, the opposite end of which abuts the ring 118. The pin 121 cooperates with the ring 119 to limit movement of the ejector pin 120 under the influence of the spring 122. The free end 123 of the ejector pin 120 is greatly reduced in size, and is sharp, as is clearly indicated in Fig. 2. The ejector body 116 is formed, beneath the ejector pin 120, with a slot 124, for a purpose later to be described.

The toggle-trip mechanism

A screw or pin 125, supported in the end wall 108 of the strap 106, forms a journal mounting for a trip lever 126 most clearly illustrated in Figs. 5 and 7. One end of said lever is bifurcated to form legs 127 and 128, while the opposite end 129 of said lever is formed as a single finger for a purpose later to be described. The lower end of the spring 54 is secured to the leg 127, thereby performing the dual functions of biasing the pawl 47 and the lever 126 in the desired directions. The leg 128 is positioned for cooperation with the finger 166 integral with the lever 35, for a purpose later to be described.

The coin receiver

As is shown in Fig. 2, the plate portion 90 of the tumbler 87 is formed, near its upper left-hand corner, with a perforation 130 through which, as is shown in Figs. 3 and 4, passes a rivet 131 pivotally securing to said plate portion 90 a visual indicator plate 132, formed with a coin slot 133, and carrying the legends 134 and 135.

A screw 136 passes loosely through the aperture 102 in the free end of the arm 101, and mounts a spacer collar 137 before being threaded into an aperture 138 formed in the flange 139 (see Fig. 7) integral with the plate 132 and perpendicular thereto. A coiled spring 136' is received between the head of the screw 136 and the adjacent surface of the arm 101. It will thus be seen that the screw 136 and spring 136' cooperate to hold the flange 139 of the plate 132 which is pivotally mounted on the pin 131, resiliently adjacent the arm 101, the collar 137 limiting the proximity of

the flange 139 to the arm 101; but that the plate 132 and its flange 139 may be moved, against the resilient tendency of the spring 136', about the pivot 131, to increase the distance between the flange 139 and the arm 101, to facilitate the removal of litter or other foreign objects from the coin-receiving space between the arm 101 and the flange 139.

The ejector actuator

Struck up from the flange 139, as is most clearly shown in Figs. 3 and 7, is a perpendicularly projecting ear 140 upon which is threadably mounted a screw 141 formed to provide a journal mounting for an ejector arm 142 which, at its free end, carries a pin 143 projecting through the slot 124 in the ejector body 116. A finger 145 on said arm 142 provides an anchorage for one end of a spring 144, the opposite end of which is anchored to a finger 146 projecting downwardly from the flange 139, whereby said arm 142 is resiliently held against counterclockwise movement.

As is most clearly illustrated in Fig. 7, the flange 139 is formed with an aperture 147 through which projects the curved end of the coin-carrying arm 65; and it is to be noted that the aperture 147 is large enough to permit lateral shifting of said end of the arm 65 toward the left, as viewed in Fig. 7, against the tendency of the spring 67 (Figs. 3 and 6). In alignment with the ejector pin 120, the flange 139 is formed with a slot 148; and the arm 101 may be formed with a shallow groove 149 aligned with the slot 148. The ejector pin 120 operates through said slot 148.

The toggle blocker

A link 150 (see Fig. 3) is pivotally mounted at one end upon a screw or rivet 151 passing through an aperture 152 (see Fig. 2) in the lower right-hand portion of the plate 93. Adjacent its opposite end, the link 150 is formed with a slot 153, and a screw 154, formed with a large cylindrical shoulder 155 received in said slot 153, is threadedly engaged in a bore 156 in one end of a toggle lever 159 pivotally mounted at 160 upon the table portion of the strap 106. A spring 157 is anchored at one end upon a finger 150' formed on the link 150, and at its opposite end upon a cotter pin 158 secured in the wall 108 of the strap 106. It will be clear that, as the plate 93 is rotated in a clockwise direction about the axis of the plug 88, the spring 157 will tend to cause rotary movement of the link 150 about its pivot 151 in a counterclockwise direction; thereby swinging the toggle lever 159 in a clockwise direction about its pivot 160; and, after a predetermined degree of movement of the plate 93, the spring will cause the link 150 and lever 159, acting as a toggle, to swing past dead center. In that position, the shoulder 161 of the lever 159 immediately overlies the finger 129 of the lever 126.

Register actuation

A clamp element 162, adapted to be tightened by a screw 163, is sleeved upon the shaft 86 to support a lever 164 non-rotatably with respect to said shaft. A pin 165 carried by the free end of said lever 164 is received in the slot 99 of the pitman 97.

The inner and outer coverings

Referring, now, to Fig. 7, it will be seen that the above-described lock assembly may be secured to the outer surface of a door 167 or the

like through the medium of screws 168 or the like. Bolts 169 may pass through the assembly plate 20 and through the door 167 to take into threaded socketed lugs 170 on the inner surface of an inner escutcheon plate 171. The shaft 39 will be preferably received in a bushing 172 secured in place in a bore through the door 167. As is clearly shown in Fig. 7, the outer end of said shaft 39 is formed with a deep kerf 173 through which passes a pin 174 carried by the shank of the operating handle 40.

A casing or housing 175 is formed, adjacent its upper end, with a downwardly projecting lug 176 adapted to be received in the slot 177 formed adjacent the inner end of the block 71. Said housing is formed with lateral walls 178 which, in the assembled condition of the parts, overlie the edges of the assembly plate 20, and contact the outer surface of the door 167, thereby completely enclosing the above-described mechanism. One of said walls is formed with a slot 179 for accommodating the projecting portion of the latch bar 26; and is preferably formed also with a projecting shroud 180 which covers the projecting end of the latch bar to tend to prevent direct manipulation of the latch bar by a blade or other instrument inserted between the housing and the keeper. Preferably, a block 181 projects outwardly, immediately within the shroud 180, in substantial registry with the latch bar, further tending to prevent the insertion of an instrument into engagement with the latch bar; and a keeper plate 204, having a shroud 205, is adapted to be secured to the door frame, further to enclose the projecting end of the latch bar when the door is closed. Said shroud 205 is formed with a notch 206 for the accommodation of the block 181.

Suitably journalled in an escutcheon 182 is an outer operating handle 183, the inner end of which is formed with a blade 184 which, when the housing is assembled with the lock mechanism, enters the kerf 89 of the plug 88.

The front wall of the casing 175 is formed with a coin slot 185 which, when the parts are in the positions of Fig. 3, registers with the coin slot 133 in the indicator plate 132; and said wall is further formed with a window 186 with which alternatively register the legends 134 and 135 of the plate 132, depending upon the position of the tumbler 87. It will readily be seen that, when the parts are in any positions other than the positions of Fig. 3, the slot 133 in the plate 132 is out of registry with the casing slot 185, whereby the insertion of a coin into the mechanism is prevented.

The casing is further formed with a small aperture 187 which, in the assembled condition of the organization, registers with the socket 75 of the screw 72, whereby a polygonal wrench may be inserted to operate the screw 72 without removing the casing 175.

A lock barrel 188 is journalled in the front wall of the housing 175 and, within the housing, carries a lever 189 upon which is mounted a pin 190 cooperable with the ear 30 on the plate 29 secured to the latch bar 26; whereby the latch bar may be withdrawn, through the medium of a pass key, without affecting the coin controlled mechanism or the register 85. One wall 178 of the casing is formed with a window 191 which registers with the usual window in the register 85. A plate 192, formed with a window 193, adapted, at times, to register with the window 191 is formed with a vertical slot 194 through which is projected a pin 195 secured to the wall 178; and with a second

slot 196 having a bayonet arm 197, through which is projected a pin 198 secured to the wall 178. Said plate 192 is formed with an operating finger 199 projected into a position in which it is readily operable through an opening 200 in the front wall of the housing 175. Said opening 200 is normally closed by a cover 201 in which is mounted a lock barrel 202 carrying an eccentric tongue 203 adjacent the inner surface of said closure 201. Upon operation of the lock 202 to withdraw the eccentric 203 to a position within the periphery of the closure 201, the closure 201 may be removed from the opening 200, thereby rendering the interior of the casing available for removal of coins therefrom and for adjustment of the plate 192 to permit inspection of the register 85.

Operation

With the parts in the positions illustrated in Fig. 3, and with the casing in place, the slot 133 will be in registry with the casing slot 185. If a coin of proper denomination is now inserted through the slots 185 and 133, it will drop into the space between the flange 139 and the arm 101, and will be supported therein upon the arms 65 and 68. Rotation of the handle 183, now, in a clockwise direction, will be transmitted through the kerf 89 and plug 88 to the tumbler 87 and its arm 101. That movement will immediately move the slot 133 out of registry with the slot 185. Due to the great degree of difference in lever arms between the parts associated with the opposite ends of the arm 142, a very slight degree of movement of the arm 101 and plate 132 will cause a rapid movement of the ejector body 116 in a counterclockwise direction about its pivot screw 117. The sharp end 123 of the ejector pin 120 will thus be raked rapidly downwardly, through the slot 148, across the face of the coin; and said pin is so positioned, relative to the arms 65 and 68, that its movement is across an exact diameter of the coin. The strength of the spring 122 is such that, if the end 123 of the pin 120 encounters no sharp obstruction on the face of the coin, it will, as suggested above, merely rake across the face of the coin without affecting the other parts of the mechanism; and said pin will be swung past the center of the coin, and nearly to the lower periphery of the coin, before the coin comes into contact with the nose 49 of the pawl 47.

Ejector operation

Slugs of the type used in connection with slot machines are frequently dropped into the coin slots of locks of the character here under consideration. Such slugs are universally formed with central perforations. The present mechanism is so designed and proportioned that the end 123 of the ejector pin will first come into contact with the element dropped into the coin slot at a point slightly above the center thereof. If, as it rakes across the face of a slug dropped into the coin slot, the pointed end 123 of the pin 120 encounters a perforation, it will drop into that perforation; and, as it moves downwardly, it will carry the slug with it, camming the arm 65 to the left, as viewed in Fig. 7, and thereby forcing the slug out of the space between the arm 101 and the flange 139, to permit the pawl 47 to drop into the socket 103 to prevent further movement of the arm 101.

Coin-controlled latch-bar retraction

However, if a true coin has been used, the pin

120 will, as stated above, rake harmlessly past the coin. The coin, supported upon the arm 65 and 68, covers the socket 103; and cams the nose of the pawl 47 upwardly, against the tendency of the spring 54, thus permitting the tumbler 87 to continue its movement. The nose of the pawl drops off the coin just after the pawl nose passes the lower edge of the pin 105; and just after the pawl nose drops off the coin, the coin moves past the end of the arm 65, and so drops into the reservoir at the bottom of the casing 175. Nothing now prevents further clockwise movement of the arm 101, which now comes into contact with the flange 69, so that continued movement of the arm 101 retracts the latch bar 26 to permit the door to be opened.

Just after the pawl 47 rides off the coin, the finger 91 clears the finger 61, so that the spring 113, tensioned by rotation of the tumbler 87, can swing the tumbler trip 58 in a counterclockwise direction to bring the finger 61 beneath the finger 91 to hold the tumbler 87 against reverse movement. At this moment, the arm 101 is just short of contact with the flange 69, and the coin has not yet been carried beyond the end of the arm 65. In this position of the parts, the plate 132 has closed the slot 185 and both legends 134 and 135 are out of registry with the window 186. It may be mentioned here that the finger 92 comes into contact with the post 100 on the plate 93 just after the ejector pin has passed the coin, and while the pawl is still in contact with the coin. Thus, if an attempt is made to operate the lock without a coin or with a slug, the plate 93 is not moved, and therefore the register 85 will not be affected.

Once the edge 50 of the pawl 47 has been carried, across the face of a proper coin, beyond the lower edge of the head of the pin 105, there is nothing to hold the arm 101 against further movement in a clockwise direction into contact with the flange 69, and against still further movement to shift the latch bar 26, through such contact, toward the right as viewed in Figs. 1 and 2 to withdraw the latch bar from its keeper. Such movement of the tumbler 87 and its arm 101 will carry with it, through the cooperation of the finger 92 and the post 100, the plate 93. Such clockwise movement of the plate 93 will shift the pitman 97 to the left, thereby swinging the lever 164 in a clockwise direction, as viewed in Fig. 3, to register one operation of the lock upon the register 85. It also carries with it the left-hand end of the member 150; which movement, resisted by the spring 157, will swing the link 150 in a counterclockwise direction about its pivot 151 to shift the toggle lever 159 in a clockwise direction to move the finger 161 of said lever into cooperation with the finger 129 of the element 126. When the patron now releases the outer handle, the latch bar will be returned to projected position, by the spring 31, and such return movement of the latch bar will carry with it the arm 101 and the tumbler 87, the spring 110 assisting in that return movement of the tumbler 87. Such return movement of the tumbler 87, however, is limited by the engagement of the finger 61 beneath the finger 91. In this "rest position" of the mechanism, the spring 113 is substantially relaxed.

Tumbler trip operation

The patron now enters the enclosure and closes the door. As the door is closed, the beveled portion of the latch bar 26 strikes the keeper shroud

205 and is thereby forced into withdrawn position, as the latch bar passes the outer edge of the keeper shroud. Such movement of the latch bar causes the shoulder 60 to strike and shift the end 59 of the tumbler trip 58, thereby removing the finger 61 from beneath the finger 91, and permitting the tumbler 87, under the influence of the spring 110, to return to an intermediate position in which the legend 135 registers with the window 186.

The tumbler 87 is arrested in this intermediate position by the engagement of the shoulder 225 on the plate 132 with the adjacent shoulder 226 on the plate 93; said plate 93 being held against counterclockwise movement by the toggle comprising the link 150 and the lever 159, and the engagement of the finger 161 with the finger 129 of the lever 126. In this position, of course, the slot 133 is out of registry with the slot 185; the pawl 47 is so positioned that it will engage the shoulder 104 to prevent any attempt to operate the latch bar through the medium of the outer handle 183; and the lock is therefore in condition to prevent the door from being opened from the outside. In this "rest position" of the mechanism, too, the spring 113 is substantially relaxed, because its anchorage on the tumbler 87 has now been moved toward its anchorage on the trip lever 58.

Inner handle latch-bar retraction

When the patron is ready to leave the enclosure, he may do so by turning the inner handle 40 in either direction. Rotation of that handle 40 in one direction will cause the pin 38 to engage the surface 37 on the lever 35 to swing the lever 35 in a clockwise direction about its pivot 36 to retract the latch bar 26; and rotation of the handle 40 in the opposite direction will cause the pin 38 to engage the surface 43 on the lever 42 to swing the lever arm 44 in a clockwise direction to act upon the surface 45 of the lever 35 to swing said lever in a clockwise direction about its pivot 36 to retract the latch bar.

Such movement of the lever 35 will, through the finger 166, swing the element 126 in a clockwise direction, as viewed in Fig. 7, about its pivot 125 to elevate the finger 129 of said element 126. Said finger 129, acting upon the finger 161 of the latch lever 159, will move the pivot 154 in a counterclockwise direction about the pivotal point 160 to break the toggle comprising the element 159 and the link 150 past its dead center condition; whereupon the spring 110 will promptly snap the tumbler 87 back into the position illustrated in Figs. 2 and 3, wherein the slot 133 registers with the slot 185 and the legend 134 registers with the window 186. The lock is now in a condition to accept another coin for re-operation from the outside.

Blocking the latch-bar and automatically masking the coin slot

If, for any reason, it is desired to lock the enclosure to prevent access thereto, a polygonal wrench may be inserted through the perforation 187 into the socket 75 in the screw head 74, whereby the screw may be rotated to project the end 73 thereof into the path of the ear 70, whereby retraction of the latch bar will be positively prevented.

In order to prevent a patron from dropping a coin into the slot 185 while the lock is so disabled, we have provided the lever 77 and its associated parts. As has been explained herein-

above, the flared head 74 will act upon the arm 76 of the lever 77, during projection of the screw, to swing said lever in a counterclockwise direction, whereby the arm 79 of said lever will act to swing the arm 101 of the tumbler 87 in a clockwise direction. Through the action of these parts, the slot 133 is shifted out of coin-accepting registry with the slot 185 very promptly upon initiation of projecting movement of the screw 72, and long before that screw comes into obstructing relation with the ear 70. In the final position of the screw 72, the arm 101 assumes a position such that the two legends 134 and 135 on the plate 132 are both unreadable through the window 186.

If, for any reason, it should become desirable to leave the mechanism in such condition that the door may be opened without actuation of the lock, the attendant will insert a pass key in the lock tumbler 188 to withdraw the latch bar. Now, he may either hold the latch bar in withdrawn position with the latch key, or open the door and hold the latch bar in withdrawn position with his finger, while projecting the screw 72 into the path of the ear 70. In this position, the screw will hold the latch bar in withdrawn position against the tendency of the spring 31. Of course, in this condition of the parts, the slot 185 is masked, by an unperforated portion of the plate 132, and the legends 134 and 135 are both unreadable through the window 186.

Means preventing direct latch-bar manipulation

In spite of all the precautions which have been used in the past in an effort to prevent unauthorized operation of locks of the character here under consideration, one method of such unauthorized operation has not heretofore been conquered. There must necessarily be a space (though it is a small one) between the free edge of the door and its frame. A thin bladed hook, or a curved light wire can sometimes be inserted through that opening, and then worked outwardly to engage the beveled end of the latch and, ultimately, to force the latch bar out of engagement with its keeper. By a very simple expedient, disclosed herein, we have absolutely prevented such operation of the latch bar. On the inner surface of the latch bar, in a position where it lies closely adjacent to the edge of the assembly plate 20 in the fully projected position of the latch bar, we have formed a vertical notch 211. Any blade or wire which is inserted through the crack between the door edge and its frame, and which is then urged outwardly against the latch bar will find a seat in that notch 211, and will so be prevented from finding its way onto the beveled surface of the latch bar to cam the latch bar into withdrawn position.

Single-use lock

In some kinds of installations, as for instance in connection with pay shower stalls or bath rooms, it is essential that each enclosure shall be serviced by the attendant after each use, and before it is again used. In such situations, difficulties have arisen in the past by reason of the fact that sometimes the attendant will fail to notice the emergence of a patron from such a booth; and a new patron will deposit a coin and enter the booth, only to find that it has not been serviced, that there are no clean towels, and that the place is not in condition for new use. If he notices this before he has permitted the door to close, he can at least hold the door open and

shout for the attendant and, after the attendant comes and cleans the place up, he will have a private place in which to bathe. But if the patron permits the door to close before noticing the condition of the booth, the tumbler 87 will have snapped to its intermediate position, the door will be latched, and the door cannot then be opened by the patron without actuating the toggle 150, 159 to snap the lock back into the position in which it is ready to accept a new coin; so that the patron will thereafter not be able to use that booth in complete privacy without first depositing another coin.

In order to overcome this defect of the lock mechanism above described, when used in such a location, we have constructed a modified form of lock illustrated in Figs. 12 and 13. The mechanism of these figures is identical with the structure above described, except for the toggle mechanism which holds the organization in "in use" position.

In the organization of Fig. 12, there is substituted for the element 126 a similar element 212, which differs from the element 126, however, in the absence of the finger 129. In place of the toggle lever 159, we provide a toggle lever 213 pivoted at 214 intermediate its ends, upon the strap 106. Pivoted on the upper end of the lever 213, as at 215, is a long link 216, the upper end of which carries a pin 217 guided in a slot 218 formed in an ear 219 corresponding to the ear 30. The upper end of the link 216 is provided with a hooked portion 220 for a purpose later to be described. The opposite end of the lever 213 carries a pin 221 which is slidably received in the slot 153 of the link 150.

The operation of the mechanism of Fig. 12 when a coin of the proper denomination is deposited therein, is identical with the operation of the mechanism above described. As in the mechanism illustrated in Figs. 1 to 11, the actuation of the latch bar as the door closes shifts the mechanism into an intermediate "in use" position, in which the patron has undisturbed privacy. But, in the organization of Fig. 12, operation of the inner handle 40 to withdraw the latch bar, to permit the patron to emerge from the booth, does not affect the lock mechanism; and when the door is thereafter closed, the booth is locked against ingress, with the plate 132 masking the casing slot 185. Thereafter, the booth can be opened only by the use of the attendant's key.

As illustrated in Fig. 13, a lock barrel 222 mounted in the housing carries an eccentric 223 upon which is mounted an actuating pin 224 which, under normal conditions, is located substantially at the position indicated in Fig. 12, beneath the hook 220 and to the left of the ear 219. When the lock parts are in their intermediate position, with the toggle 213, 150 in its extended position, the pin 217 is substantially at the bottom of the slot 218. Operation of the lock barrel, now, will cause the pin 224 to move first upwardly to lift the hook 220 to break the toggle; and then to the right to engage the ear 219 to retract the latch bar.

Thus, once such a booth has been used, the parts remain in the intermediate position, preventing the insertion of a coin thereinto, until the attendant has opened the door with his key; whereby the attendant is necessarily reminded to service the booth before again leaving it.

We claim as our invention:

1. In a coin controlled mechanism, a coin re-

ceiver comprising a movable arm having a face portion and a portion extending rearwardly from said face portion, a plate pivotally mounted on said rearwardly extending portion and having a flange disposed in substantial parallelism with said face portion, and means cooperating with said arm and with said flange and biasing said flange toward said face portion.

2. In a coin controlled mechanism, a coin receiver comprising a movable arm having a face portion and a portion extending rearwardly from said face portion, a plate pivotally mounted on said rearwardly extending portion and having a flange disposed in spaced substantial parallelism with said face portion, and means cooperating with said arm and with said flange and biasing said flange toward said face portion, said plate being formed with a coin receiving slot registering with the space between said flange and said face portion.

3. In a coin controlled mechanism, a coin receiver comprising a movable arm having a face portion and a portion extending rearwardly from said face portion, a plate pivotally mounted on said rearwardly extending portion and having a flange disposed in substantial parallelism with said face portion, an element secured to said flange and passing through said arm, and spring means cooperating with said arm and with said element and biasing said flange toward said face portion.

4. In a coin controlled mechanism, a coin receiver comprising a movable arm having a face portion and a portion extending rearwardly from said face portion, a plate pivotally mounted on said rearwardly extending portion and having a flange disposed in substantial parallelism with said face portion, an element secured to said flange and passing through said arm, a spacer member carried on said element between said flange and said face portion, and spring means cooperating with said element and resiliently holding said flange and said face portion in contact with opposite sides of said spacer member.

5. In a coin controlled mechanism, a coin receiver comprising a movable arm having a face portion and a portion extending rearwardly from said face portion, a plate pivotally mounted on said rearwardly extending portion and having a flange disposed in substantial parallelism with said face portion, a headed element passing freely through said arm and secured to said flange, and a coiled spring sleeved on said element and abutting the head of said element and the rear surface of said arm at its opposite ends, respectively.

6. In a coin controlled mechanism, a coin receiver comprising a movable arm having a face portion and a portion extending rearwardly from said face portion, a plate pivotally mounted on said rearwardly extending portion and having a flange disposed in substantial parallelism with said face portion, a headed element passing freely through said arm, supporting a spacer member between said face portion and said flange, and secured to said flange, and a coiled spring sleeved on said element and abutting the head of said element and the rear surface of said arm at its opposite ends, respectively.

7. In a coin controlled lock, a reciprocable latch bar, spring means biasing said latch bar toward projected position, means for retracting said latch bar, a trip element having a portion disposed in the path of said latch bar whereby said element is shifted by retraction of said latch

bar, and a coiled spring associated with said trip element, said coiled spring having one end anchored to said trip element and its other end anchored at a point removed from the point of anchorage of the first-mentioned end by a distance substantially equal to the collapsed length of said spring.

8. In a coin controlled lock, a reciprocable latch bar, spring means biasing said latch bar toward projected position, means for retracting said latch bar, a trip element having a portion disposed in the path of said latch bar whereby said element is shifted by retraction of said latch bar, and a coiled spring associated with said trip element, said coiled spring having one end anchored to said trip element and its other end anchored at a point removed from the point of anchorage of the first-mentioned end by a distance substantially equal to the collapsed length of said spring, said two anchorage points defining an acute angle with the line of movement of said first anchorage point.

9. In a coin controlled lock, a reciprocable latch bar, spring means biasing said latch bar toward projected position, means for retracting said latch bar, a trip element having a portion disposed in the path of said latch bar whereby said element is shifted by retraction of said latch bar, and a coiled spring associated with said trip element, said coiled spring having one end anchored to said trip element and its other end anchored at a point removed from the point of anchorage of the first-mentioned end by a distance substantially equal to the collapsed length of said spring, said two anchorage points defining an acute angle greater than 45° with the plane of movement of said first anchorage point.

10. In a coin controlled lock, a reciprocable latch bar, spring means biasing said latch bar toward projected position, a trip element having a portion disposed in the path of said latch bar whereby said element is shifted in a single plane by retraction of said latch bar, an oscillable, coin controlled tumbler for retracting said latch bar, a coiled spring having one end anchored on said element and having its other end anchored on said tumbler, the distance between the points of said two anchorages when said lock is in position to receive a coin being substantially equal to the collapsed length of said coiled spring, latch-retracting movement of said tumbler moving said tumbler anchorage away from said element anchorage, and means normally disposed in the path of said element but withdrawn from said path by such movement of said tumbler to permit movement of said element under the influence of said coiled spring in a direction opposite to the direction in which it is moved by retraction of said latch bar, thereby substantially restoring the above-mentioned distance between said anchorages.

11. In a coin-controlled lock, a reciprocable latch bar, spring means biasing said latch bar toward projected position, a trip element having a portion disposed in the path of said latch bar whereby said element is shifted in a single plane by retraction of said latch bar, an oscillable, coin controlled tumbler for retracting said latch bar, a coiled spring having one end anchored on said element and having its other end anchored on said tumbler at a point outside said plane, the distance between the points of said anchorages when said lock is in position to receive a coin being substantially equal to the col-

lapsed length of said coiled spring, latch-retracting movement of said tumbler moving said tumbler anchorage away from said element anchorage, and means normally disposed in the path of said element but withdrawn from said path by such movement of said tumbler to permit movement of said element under the influence of said coiled spring in a direction opposite to the direction in which it is moved by retraction of said latch bar, thereby substantially restoring the above-mentioned distance between said anchorages.

12. In a coin controlled lock, a reciprocable latch bar, spring means biasing said latch bar toward projected position, a trip element having a portion disposed in the path of said latch bar whereby said element is shifted in a single plane by retraction of said latch bar, an oscillable, coin controlled tumbler for retracting said latch bar, a coiled spring having one end anchored on said element and having its other end anchored on said tumbler at a point outside said plane, a line defined by said two points of anchorage defining an acute angle with said plane.

13. In a coin controlled lock, a reciprocable latch bar, spring means biasing said latch bar toward projected position, a trip element having a portion disposed in the path of said latch bar whereby said element is shifted in a single plane by retraction of said latch bar, an oscillable, coin controlled tumbler for retracting said latch bar, a coiled spring having one end anchored on said element and having its other end anchored on said tumbler at a point outside said plane, a line defined by said two points of anchorage defining an acute angle greater than 45° with said plane.

14. In a coin controlled lock, a reciprocable latch bar, spring means resisting retraction of said latch bar, a coin-controlled, oscillable tumbler operable to retract said latch bar, a trip element cooperable with said tumbler and having a portion disposed in the path of said latch bar whereby said element is shifted by retraction of said latch bar, and a coiled spring having one end anchored on said trip element and its other end anchored on said tumbler, said mechanism having a plurality of rest positions in which the distance between the anchorage points of said coiled spring is substantially equal to the collapsed length of said spring.

15. In a coin controlled lock, a reciprocable latch bar, spring means resisting retraction of said latch bar, a coin-controlled, oscillable tumbler operable to retract said latch bar, a trip element cooperable with said tumbler and having a portion disposed in the path of said latch bar whereby said element is shifted by retraction of said latch bar, and a coiled spring having one end anchored on said trip element and its other end anchored on said tumbler, said mechanism having a plurality of rest positions in which the distance between the anchorage points of said coiled spring is substantially equal to the collapsed length of said spring, movement of said trip element by retraction of said latch bar increasing that distance.

16. In a coin controlled lock, a reciprocable latch bar, spring means resisting retraction of said latch bar, a coin-controlled, oscillable tumbler operable to retract said latch bar, a trip element cooperable with said tumbler and having a portion disposed in the path of said latch bar whereby said element is shifted by retraction of said latch bar, and a coiled spring hav-

ing one end anchored on said trip element and its other end anchored on said tumbler, said mechanism having three rest positions in which the distance between the anchorage points of said coiled spring is substantially equal to the collapsed length of said spring.

17. In a coin controlled lock, a reciprocable latch bar, spring means resisting retraction of said latch bar, a coin-controlled, oscillable tumbler operable to retract said latch bar, a trip element cooperable with said tumbler and having a portion disposed in the path of said latch bar whereby said element is shifted by retraction of said latch bar, and a coiled spring having one end anchored on said trip element and its other end anchored on said tumbler at a point spaced from the line of movement of said element anchorage, said mechanism having a plurality of rest positions in which the distance between the anchorage points of said coiled spring is substantially equal to the collapsed length of said spring.

18. In a coin controlled lock, a reciprocable latch bar, spring means resisting retraction of said latch bar, a coin-controlled, oscillable tumbler operable to retract said latch bar, a trip element cooperable with said tumbler and having a portion disposed in the path of said latch bar whereby said element is shifted by retraction of said latch bar, and a coiled spring having one end anchored on said trip element and its other end anchored on said tumbler, said anchorages defining a line making an acute angle with the line of movement of said element anchorage.

19. In a coin-controlled mechanism, a coin-controlled, oscillable member, an element independently mounted for oscillation about a common axis with said member, means limiting relative oscillation of said member and said element in opposite directions, a toggle mechanism associated with said element, spring means operable to snap said mechanism past dead center, upon movement of said element to a predetermined degree in one direction, to block movement of said element and said member in the opposite direction, and means independent of said element and said member for breaking said toggle mechanism.

20. A coin-controlled lock mechanism comprising a reciprocable latch bar biased to projected position, a shaft, an element operatively associated with said shaft and shiftable by oscillation of said shaft to retract said latch bar, a tumbler coaxial with said shaft and oscillable relative thereto, a coin carriage arm movable with said tumbler, means normally blocking movement of said tumbler in one direction but rendered ineffective by the presence of a coin on said arm, cooperative means on said arm and on said latch bar adapted, at times, to provide a driving connection therebetween, a tumbler trip lever pivotally mounted and having an arm positioned in the retractive path of said latch bar, cooperative means on said trip lever and on said tumbler operable, upon movement of said tumbler in a latch-retracting direction, to block return movement of said tumbler, spring means tensioned by such movement of said tumbler to urge said trip lever into blocking relation, said trip lever being movable, by subsequent retraction of said latch bar, out of blocking relation with said tumbler, a member mounted for coaxial oscillation relative to said tumbler, cooperating means on said tumbler and on said member providing a one-way driving means therebetween only after prelimi-

nary movement of said tumbler through a predetermined angle, toggle means associated with said member and operable, after movement of said member through a predetermined angle, to block return movement of said member, other cooperating means on said member and on said tumbler limiting return movement of said tumbler while said member is blocked, and means operated by latch-retracting movement of said first-mentioned element to break said toggle to permit return movement of said member and said tumbler.

21. The combination with a reciprocable latch bar and means biasing said latch bar toward projected position, of a shaft, means projecting from said shaft, a lever pivotally mounted adjacent said shaft and projecting into cooperative relation with said latch bar, said lever having a surface engageable by said projecting means, upon oscillation of said shaft in one direction, to shift said lever in latch-retracting direction, and a second lever pivotally mounted adjacent said shaft and having an arm cooperatively associated with said first-mentioned lever, said second lever having a surface engageable by said projecting means, upon oscillation of said shaft in the opposite direction, to shift said second lever in a direction to shift said first-mentioned lever in latch-retracting direction.

22. A coin-controlled lock mechanism comprising a reciprocable latch bar biased to projected position, a shaft, an element operatively associated with said shaft and shiftable by operation of said shaft to retract said latch bar, a tumbler coaxial with said shaft and oscillable relative thereto, a coin carriage arm movable with said tumbler, means normally blocking movement of said tumbler in one direction but rendered ineffective by the presence of a coin on said arm, cooperative means on said arm and on said latch bar adapted, at times, to provide a driving connection therebetween, a tumbler trip lever pivotally mounted and having an arm positioned in the retractive path of said latch bar, cooperative means on said trip lever and on said tumbler operable, upon movement of said tumbler in a latch-retracting direction, to block return movement of said tumbler, spring means tensioned by such movement of said tumbler to urge said trip lever into blocking relation, said trip lever being movable, by subsequent retraction of said latch bar, out of blocking relation with said tumbler, a member mounted for coaxial oscillation relative to said tumbler, cooperating means on said tumbler and on said

member providing a one-way driving means therebetween only after preliminary movement of said tumbler through a predetermined angle, toggle means associated with said member and operable, after movement of said member through a predetermined angle, to block return movement of said member, other cooperating means on said member and on said tumbler limiting return movement of said tumbler while said member is blocked, and means independent of said tumbler and of said shaft for breaking said toggle to permit return movement of said tumbler and said member.

23. In a coin-controlled mechanism, a coin-controlled, oscillable member, an element independently mounted for oscillation about a common axis with said member, means limiting relative oscillation of said member and said element in opposite directions, a toggle mechanism associated with said element, spring means operable to snap said mechanism past dead center, upon movement of said element to a predetermined degree in one direction, to block movement of said element and said member in the opposite direction, and means operable only by a removable key for breaking said toggle mechanism.

24. In a coin-controlled lock, a latch-bar, a coin-controlled oscillable member operable, upon the deposit of a coin, to retract said latch-bar, a housing for the lock mechanism provided with a coin slot, means shiftable with said member to mask said slot, toggle mechanism operable, upon movement of said member to latch-retracted position, to block said masking means against return to slot-clearing position, and means operable only by a removable key for breaking said toggle mechanism.

25. In a coin controlled mechanism, a device to be operated, an oscillable member, a coin carrier movable with said member, a slug ejector mechanism operable through its entire stroke by initial movement of said member and effective to remove a slug from said carrier, blocking means located in the path of said carrier to arrest movement of said member after completion of said ejector stroke and before operative connection is established between said member and said device, said blocking means being rendered ineffective by a coin on said carrier, a register, and an element, movable by said member only by such movement of said member as will operate said device, to advance said register.
